UNITED STATES PATENT OFFICE.

HARVEY R. HAYWARD, OF AKRON, OHIO.

TOY.

Application filed May 7, 1921. Serial No. 467,633.

To all whom it may concern:

Be it known that I, HARVEY R. HAYWARD, a citizen of the United States, residing at Akron, in the county of Summit and State 5 of Ohio, have invented new and useful Improvements in Toys, of which the following is a specification.

My present invention has reference to a balanced toy, and has for its object to produce a toy of this character provided with figures representing persons or animals and susceptible to both a swinging and a rotary movement, whereby certain of the figures will be caused to simulate pursuers and pursued.

A further object is to produce a balanced toy of an extremely simple construction, which may be easily operated and which will afford both instruction and amusement.

The foregoing, and other objects which will appear as the nature of the invention is better understood, may be accomplished by a construction, combination and operative association of parts, such as is disclosed 25 by the drawings which accompany and which form part of this application.

In the drawings:—

Figure 1 is a side elevation of a toy in accordance with this invention.

Figure 2 is a top plan view thereof.

Figure 3 is a sectional view on the line 3—3 of Figure 2.

Figure 4 is a sectional view on the line 4—4 of Figure 1.

Figure 5 is a detail side elevation, partly in section illustrating the manner in which the pointed member is received in the depression in the widened end of the rod 14.

Referring now to the drawings in detail, 40 the numeral 1 designates a flat base piece which has arising therefrom a thin rod 2 that has its outer end pointed, as at 3.

The numeral 4 broadly indicates a frame which is V-shaped in plan. The side members of the frame are indicated by the numeral 5 respectively, the same having their confronting faces at their meeting ends beveled or cut angularly and connected together in any desired or preferred manner.

50 The sides, adjacent the front or pointed end of the frame are held in spaced relation by a transverse brace 6. The ends of the side members 5 are provided with weights 7.

Preferably the spread ends of the sides are 55 provided with pockets 8 in which the

weights 7 are concealed, the said pockets having their outer portions closed by elements 9, and passing through these closures and engaging with the weights are longitudinally adjustable elements 10, whereby the weights may be brought toward the outer or inner ends of the pockets to properly weight the spread end of the frame.

The frame has on its top, at its outer pointed end figures 11 which, in the present instance, represent a horse and a rider. The side members of the frame, on their upper faces and at their weighted ends are provided with figures 12 which, in the present instance, represent running men.

Centrally secured to the pointed end of the frame, and also braced to the cross piece 6, as at 13, is a rod 14. This rod terminates inward of the open end of the frame, and the outer end of the said rod is flattened, as at 15 and may be provided, on its under face with a cup-shaped depression 16 to receive therein the pointed end 3 of the rod 2. When the frame rests on the rod the weights are properly adjusted so that the said frame will assume a horizontal position on the base. The frame may be tilted, and being counter-balanced, will swing of its own accord, on the rod 2, for a comparatively long period of time. The frame may be turned horizontally on its pivotal support provided by the rod 2 and revolved so that the inner figures 12 will present the appearance of pursuing the outer figures 11.

The toy is of an extremely simple construction, may be cheaply manufactured and marketed, and will, as previously stated, afford both amusement and instruction. The fulcrum rod 2 is detachably associated with the base, and the frame is likewise detachably associated with the fulcrum rod, so that when the toy is not in use, the parts thereof may be folded into a compact bundle for storage or shipment.

Having described the invention, I claim:—
1. A toy as herein described, including a substantially V-shaped frame having figures at the apex and on the ends thereof and having a rod centrally arranged therein, terminating in a widened portion having a cup-shaped depression, brace means between the arms of the frame and the said rod, a fulcrum member having a pointed end received in the cup-shaped depression of

the rod, and weighted means in the outer ends of the arms of the frame adjustable exteriorly thereof.

2. A toy, as herein described, comprising
5 a substantially V-shaped frame, a rod arranged centrally between the arms of the frame, a brace disposed transversely between the arms of the frame and secured to the rod, a fulcrum member on which the
10 outer end of the rod rests, the arms of the frame having their outer ends formed with

pockets, and plates closing the pockets, screw members having outer headed ends journaled in the plates and in the inner walls of the pockets, and weights in the 15 pockets having threaded bores engaged by the screws whereby said weights may be adjusted longitudinally in said pockets.

In testimony whereof I affix my signature.

HARVEY R. HAYWARD.
